Des. 238,777

Patented Feb. 10, 1976

238,777

GUTTER FOR BUILDINGS

Raymond Rodney McSherry-Rhoades, 72 Jenkins Grove,
Copnor, Portsmouth, Hampshire, England

Filed Sept. 11, 1973, Ser. No. 396,304

Term of patent 14 years

Int. Cl. D25—02

U.S. Cl. D13—1 H

FIG. 1.

FIG. 2.

FIG. 1 is a perspective view of a gutter for buildings showing my new design with portions broken away in part to indicate indeterminate length; and

FIG. 2 is an end elevation.

I claim:

The ornamental design for a gutter for buildings, substantially as shown and described.
